HUMIDIFIER

Josiah M. Ayer and John P. Ayer, Portland,
Maine

Application May 27, 1931. Serial No. 540,432

9 Claims. (Cl. 237—78)

The present invention relates to improvements in humidifiers, and has for an object to provide an improved humidifier for the conditioning of indoor atmosphere or enclosed air whereby to maintain a proper percentage of moisture or humidity for the health and comfort of mankind.

Temperature affects the humidity in an inverse ratio, so that, other things being equal the warmer the air the lower the humidity and the greater the requirement for moisture. Humidifiers correctly designed and efficiently attached to radiators should therefore maintain an even and healthful percentage of moisture in the air of dwellings or other enclosures.

It is an object of the invention to provide an improved water vessel or container having a new and improved cooperation in common with the various types and styles of radiators.

It is also an object of the invention to provide improved, adjustable and universal suspension means for the water container whereby such container may be supported at the correct elevation and upon radiators of various styles and types.

The invention also contemplates a varied construction of suspension band or other means for effecting connection between the water container and the suspension chain.

With the foregoing and other objects in view, the invention will be more fully described herein-after, and will be more particularly pointed out in the claims appended hereto.

In the drawings, wherein like symbols refer to like or corresponding parts throughout the several views,

Figure 1 is a perspective view showing an improved humidifier constructed in accordance with the present invention.

Figure 2 is a top plan view of one type of radiator showing the method of attachment of the improved humidifier.

Figure 3 is a vertical section taken on the line 3—3 in Figure 2.

Figure 4 is a similar view showing the device applied to a different type of radiator.

Figure 5 is a top plan view of the water container with a modified form of suspension plate or strap.

Figure 6 is a rear elevation of the same.

Figure 7 is a top plan view of the water container showing a modified form of suspension band.

Figure 8 is a rear elevation thereof.

Figure 9 is a top plan view of a water container showing a further modified form of the suspension band.

Figure 10 is a rear elevation of the same.

Figure 11 is a top plan view of a water container showing a further modification of the container and suspension band.

Figure 12 is a rear elevation of the same.

Figure 13 is a horizontal section taken on the line 13—13 in Figure 12.

Figure 14 is a top plan view of a further modified form of the container, and suspension band, and

Figure 15 is a rear elevation of the same.

Referring more particularly to the drawings in Figures 1 to 3 we have illustrated a container for the water, which container may be made of sheet metal, glass or any desired material in a desired form, preferably in that form as illustrated, which consists of the front wall 20, rear wall 21, end walls 22 and 23 and the bottom 24. Preferably the end walls 22 and 23 are narrow and the front and rear walls 20 and 21 of considerable width, whereby a flat rectangular container of suitable capacity is provided with its upper portion open to leave the surface of the body of water or other liquid in the container freely accessible to the indoor atmosphere.

The indoor atmosphere will take up this moisture, the evaporation of which will be promoted and facilitated by the proximity of the container to the steam, hot water, vapor or other radiator indicated at 25.

The rear wall 21 is constructed peculiarly in that it is provided with the rearwardly offset central portion composed of the diagonal or V-shaped convergent walls 26, the apex of which is provided with a groove 27 for providing a seat for the suspension wire or band 28. This suspension wire passes all about the container in a vertical direction and the ends thereof may be concealed and secured within a sleeve or tube 29 extending across the upper open portion of the container; or the ends of this wire may be electrically welded.

At a point above the center of gravity the rear leg of the suspension wire 28 carries a loop or hook 30 engaged by a suspension chain 31 having an appropriate number of links, any one of which may be selectively engaged by the open hook 32 of the suspension yoke 33. This yoke may be made of tempered steel wire or other material of preferably a semi-circular shape, with the hook 32 bent outwardly and reversely at one end.

In Figures 2 and 3 there is shown a 5-column sectional radiator in which the hub of the radi-

ator is indicated at 34. This hub forms the support over which the yoke 33 is engaged.

In the use of the device the humidifier may be suspended, for example, as indicated in Figures 2 and 3. By engaging one or another link of the chain 31 with the hook 32 the water container may be raised or lowered and maintained at the proper or desired elevation to secure the best results and to place same within the influence of the heat from the radiator 25. It will be noted that the V-shaped offset from the rear wall 21 of the water container fits within the two adjacent sections of the radiator 25 and the flat portions of the rear wall 21 at opposite sides thereof rest against adjoining sections. In this way the device is positioned easily and freely against the front or rear portion of a radiator and has the desired contact with the radiating sections whereby to bring the water in the container under the influence of the heat and thus evaporate same in proportion to the heat giving capacity of the radiator.

It will be noted that there is one vertical offset 26, so that the device can be attached for efficient operation to any make or type of radiator in service. The offset 26 is preferably centrally located, so as to hang vertically between two sections of the radiator. The remainder of the rear wall 21 next to the radiator is a plain surface making uniform and complete contact with the radiator sections, giving the greatest heating effect to the water in the humidifier.

The center to center distance between the sections of different types and makes of radiators varies and, therefore, if there is more than one offset 26 a perfect contact between the water container and radiator is not possible. Perfect contact is necessary for efficient evaporation of the water. The water container will, of course, be scientifically designed as to capacity whereby to give the correct percentage of humidity to the air.

In Figure 4, we have shown a different type of radiator 25^a having the spacing lugs 35 over which the suspension yoke 33 is adapted to be passed; thus the weight of the humidifier, which is transmitted by the chain 31 through the hook 32 will be directly supported upon the lugs 35.

In case the offset is not provided with a groove, a suspension band 36, such as shown in Figures 7 and 8 may be provided. This is a flat metallic band encircling the container vertically as in the case of the suspension wire 28. However the flat band 36 admits of being folded angularly or bent into a substantially right angle form with parts fitting against both of the diagonal walls 26 of the offset. This band, in case of a glass container, protects the apex of the offset against breakage. A loop 37 is provided in this band to which to attach the supporting chain 31.

In the case of a metal humidifier a band or plate 38 may be provided as shown in Figures 5 and 6 having simply two angled plates fitting against the opposite convergent walls 26 of the offset and having the loop or eye 39 for the chain.

Also any of the bands may surround the humidifier or water container horizontally in a groove on the rear wall 21, but preferably above the center of gravity; or these suspension wires or bands may be embedded horizontally in the body of the water container at a distance above the center of gravity such as the band 40, shown in Figures 9 and 10. This band 40 has the loop 41 for connection to the attaching chain 31.

The purpose of the horizontal groove for the

horizontal band is to recess the band below the surface of the rear wall 21 so that this wall shall come in perfect contact, its entire vertical length, with the radiator sections 25.

The suspension chain 31 is made of sufficient length, so that the humidifier may be attached to the widest radiators made, as well as to the narrowest. One end of the chain 31 is preferably permanently fastened to the loop in the suspension band so that the humidifier, suspension band and chain are fabricated into a single member or unit.

Most efficient evaporation for properly humidifying the air is obtained when the top of the humidifier is near the top of the radiator. This is also the position of greatest convenience in filling the water container. Once hung on the radiator, this humidifier need never be removed as it can readily be refilled, access thereto being easy at all times.

In the above mentioned position, it is also easy to see where the water level stands in the humidifier, so that it may be refilled from time to time, a necessary factor in its operation.

Referring more particularly to Figures 11 and 12, a tapered form of water container is shown consisting of the upper section 42 and the lower section 43. Both sections may be tapered; or the upper section may be tapered from the top down to a groove 44 extending horizontally about the container for receiving and holding therein the suspension band 45.

Referring to Figures 14 and 15, the upper section 46 of the container is wider than the lower section 49, being provided with an overhang or shoulder on the end walls beneath which the band, which extends in a horizontal direction in a groove 47 in rear wall 21 may engage for the support of the container.

Instead of the overhang or shoulder on the end walls 22 and 23, beads or lugs may be positioned horizontally around the container for supporting the horizontal suspension band.

The container may be made of glass or other material having one offset section with the suspension bands arranged in various ways as indicated. The chain provides flexibility and allows adjustment.

In the application of suspension type of humidifier to various makes and types of radiators, a number of variables are encountered, which must be considered in the construction of the humidifier in order that it may function properly in imparting moisture to the surrounding air, which is made abnormally dry by the heat radiating from the radiator.

Thus, since the horizontal spacing of the sections of different radiators varies, we provide a humidifier with only one V-shape element on the side of the container adjacent to the radiator, so that the flat portions of this side may fit accurately against the radiator sections, whatever the section spacing may be.

Also, since the width of different radiators varies, we provide a suspension chain composed of numerous links, one end of the chain being permanently attached to the suspension plate on the container, whereby the suspension may be lengthened or shortened through cooperation of this chain with an inflexible suspension yoke, designed to engage the various links of the chain and having a capacity to hang over the hub or over the lugs and the rods of different radiators; this flexible suspension means compensates for different widths of radiators so that accurate and

efficient attachment of the humidifier thereto is attained.

It is obvious that various changes and modifications may be made in the details of construction and design of the above specifically described embodiments of this invention without departing from the spirit thereof, such changes and modifications being restricted only by the scope of the following claims.

10 What is claimed is:—

1. A humidifier adapted for use on a radiator having a plurality of spaced vertical heating sections, comprising an elongated, open-top water container, having one V-shaped, outwardly converging portion on one wall of said container extending for the full height thereof, a suspension plate, having a loop thereon, fixed on said V-shaped portion above the midway point, vertically, of said container, a chain having a plurality of links, one of which being secured to said loop, and a yoke, having a hook on one end adapted to engage, selectively, the said links, and to be supported on and hung from a transversely central point on said radiator, whereby said container may be suspended from a point separated both vertically and horizontally from the attaching point of said chain therewith, said suspending means calculated to maintain a yieldable contact of said container with the edges of said radiator sections and to maintain the V-shaped portion between said radiator sections.

2. A humidifier for heating radiators having spaced vertical sections comprising an elongated, open-top water-holding container, having one V-shaped lateral extension, the sides of which are outwardly converging, disposed on and forming a part of one wall of said container, a suspension plate on said extension, above the mid-way point of its height, a loop on said suspension plate, a chain making connection with said loop, a yoke, having a hook on one end adapted to selectively engage the links in said chain, said yoke and chain being of such construction that the length thereof may be varied in order that the same extend obliquely upwardly from the container when the device is inserted on a radiator.

3. Apparatus of the class described adapted for use on a radiator having a plurality of spaced vertical heating sections, comprising in combination an open-top water-holding container, having one V-shaped element, with outwardly converging sides, vertically and centrally disposed on and forming a part of one wall of said container and extending the full height thereof, a suspension plate fixed on and located above the vertical central point of said element, a loop on said suspension plate, a chain, one end of which is secured to said loop, a yoke shaped to be detachably hung from the upper, central portion of said radiator, between two adjacent sections, a hook on one end of said yoke adapted to engage, selectively, the links of said chain, whereby said container may be predeterminedly located and suspended in various positions on and vertically of said radiator.

4. A humidifier adapted for use on a radiator having a plurality of spaced vertical heating sections, comprising an elongated open-top water container having in its rear wall for positioning against the radiator a single vertically elongated substantially V-shaped projection adapted to freely enter between two adjacent heating sections of the radiator whereby to center the container, a band passing vertically about said container and projection, a hook member engaged

with a radiator part, and a flexible connection between said hook member and the band at a point intermediate the height of the container.

5. A humidifier for use in connection with radiators having a plurality of spaced vertical heating sections, comprising a container for liquid having an open top and a single substantially V-shaped projection in its rear wall extending vertically and adapted to fit freely between adjacent heating sections of the radiator, a band passing vertically about the container in line with the apex of the V-shaped projection, said band extending across the open top of the container and constituting a handle, and flexible supporting means connecting with the band at a point intermediate the height of the container.

6. A humidifier for radiators having a plurality of spaced vertical heating sections, comprising a substantially rectangular liquid container having an open top with a substantially V-shaped projection in its rear wall adapted to enter the space between adjacent radiator sections, the apex portion of the projection being grooved vertically, a band passing transversely and vertically about said container and situated at the rear in the grooved portion of the projection, said band also extending transversely across the upper open top of the container, a flexible chain coupled to the rear portion of the band at a point intermediate the height of the container, and a hook carried by said chain for engaging with a portion of the radiator.

7. A humidifier adapted for use on a radiator having spaced vertical sections comprising a water-holding container and suspending means, said water-holding container having a vertically extending projecting portion positioned on the side of the container which contacts the radiator when the device is suspended thereon, said vertically extending portion being shaped to fit between two of said sections, said suspending means comprising a portion so shaped as to engage a portion of the radiator and another portion flexibly connected to the container in such a manner that movement between the container and suspending means in all directions is provided for, the flexible connection portion of said suspending means being connected to the container at a point of such distance beneath the top of the container as to provide a substantial bearing surface between the point of support and the top of the container.

8. A humidifier adapted for use on a radiator having spaced vertical sections comprising a water-holding container and suspending means, said water-holding container having a vertically extending substantially V-shaped element positioned on the side of the container which contacts the radiator when the device is suspended thereon, said suspending means comprising a portion so shaped as to engage a portion of the radiator and another portion flexibly connected to the container in such a manner that movement between the container and suspending means in all directions is provided for, the flexible connection portion of said suspending means being connected to the container at a point of such a distance beneath the top of the container as to provide a substantial bearing surface between the point of support and the top of the container, said suspending means being of such construction that its length may be varied in order that it extend obliquely upwardly from

the container when the device is installed on a radiator.

9. A humidifier adapted for use on a radiator having spaced vertical sections comprising a water-holding container and suspending means, said water-holding container having one vertically extending V-shaped element positioned on the side of the container which contacts the radiator when the device is suspended thereon, said suspending means comprising a portion so shaped as to engage a portion of the radiator and another portion flexibly connected to the container in such a manner that movement between the container and suspending means in all directions is provided for, the flexible connection portion of said suspending

means being connected to the container at a point of such a distance beneath the top of the container as to provide a substantial bearing surface between the point of support and the top of the container, said suspending means being of such construction that its length may be varied in order that it extend obliquely upwardly from the container when the device is installed on a radiator, said V-shaped element having sides converging outwardly from, forming a part of, and coextensive in height with one side of said container, said element being disposed, when said device is in position on a radiator, between two adjacent sections of said radiator.
